STITCHING MACHINE

Joseph W. Bedard, Hoosick Falls, N. Y.

Application February 5, 1941, Serial No. 377,502

13 Claims. (Cl. 112—242)

This invention relates to stitching machines, and especially to the thread-feeding mechanism employed in such machines.

In the operation of such machines, the thread is usually pulled directly from a supply spool through a tensioning device and fed to the stitch-forming mechanism by means of a so-called thread take-up device. It has long been recognized, however, that this arrangement is unsatisfactory due, primarily, to the fact that when the withdrawal of the thread from the spool is abnormally resisted as it is frequently by virtue of imperfections in the thread or in the manner in which the thread is wound on the spool an imperfect stitch results.

In accordance with the present invention, the above noted as well as other difficulties are obviated by providing such machines with means arranged between the usual tensioning device and the spool and adapted to withdraw a given quantity of thread from the spool and to store the same in slack condition for subsequent use in the formation of a stitch. To this end, the machine is equipped with an attachment presenting an upper thread supply station arranged in proximity to the spool, a lower thread receiving station arranged adjacent to the tensioning device, an intermediate spring actuated clamping device and mechanism controlled from the main drive shaft of the machine operating to transfer alternately first a given length of thread from the spool to the upper supply station and then from the upper supply station to the lower receiving station during each machine cycle of operation.

In the embodiment of the invention illustrated, such mechanism includes a T-shaped rocker arm provided with a pair of laterally projecting pins or rods—one for drawing the thread from the spool into the upper supply station and the other for transferring the thread thus drawn from the spool into the lower receiving station. The rocker arm is also provided with a cam plate for controlling the operation of the clamping device so that the thread will be held against transfer between the stations as it is drawn from the spool and then freed to permit the transfer of the thread from the supply station to the receiving station from whence it may be drawn to complete a stitch.

For a more complete description of the present invention reference may be made to the accompanying drawings wherein:

Figure 1 is a side view of the thread-feeding attachment employed in the present embodiment

of the invention showing the positions of the various parts at one phase of its cycle of operations;

Figure 2 is a perspective view of a thread guide which is employed with the thread-feeding attachment shown in Figure 1;

Figure 3 is another side view of the thread-feeding attachment employed in the present embodiment of the invention showing the positions of the various parts at another phase of its cycle of operations;

Figure 4 is a front view of the thread-feeding attachment, the view being taken along line 4—4 of Figure 3;

Figure 5 is a sectional view taken along the line 5—5 of Figure 3;

Figure 6 is a perspective view of a modified form of thread guide which may be employed; and

Figure 7 is a detailed view of the rock shaft employed to effect the opening and closing of the thread-clamping mechanism.

In the embodiment of the invention illustrated, the thread-feeding mechanism is presented in the form of an attachment that may be applied to new or used machines of the type that requires three threads to complete a stitch, but it is to be understood that it may be employed with equally favorable results with machines that require the use of a greater or less number of threads to complete a stitch.

In such machines, the threads 14 which usually lead directly from supply spools 18 are drawn through tensioning devices 19 by means of a take-up device 17 and then delivered to the stitch-forming mechanism (not shown). The manner in which the take-up device 17 and the stitch-forming mechanism operates is well known in the art and a description thereof is not deemed necessary other than to say that the operation is effected by the main drive shaft 16 of the machine which makes one complete rotation during each machine cycle of operation.

The attachment comprises a vertically disposed frame member 15 secured to the main frame of the machine. The frame member 15 is provided with a thread supply station 21 and with a thread receiving station 22 located above and below a thread clamping device 23. The frame member 15 is also provided with a fore-and-aft T-shaped rocker arm 26 which is pivotally secured to the side face thereof by a stud 26a. The rocker arm 26 at its front end, is provided with a pair of laterally disposed and vertically spaced pins 24, 25, behind which the

attachment 15 is provided with a vertically disposed frame member 15 secured to the main frame of the machine. The frame member 15 is provided with a thread supply station 21 and with a thread receiving station 22 located above and below a thread clamping device 23. The frame member 15 is also provided with a fore-and-aft T-shaped rocker arm 26 which is pivotally secured to the side face thereof by a stud 26a. The rocker arm 26 at its front end, is provided with a pair of laterally disposed and vertically spaced pins 24, 25, behind which the

threads 14 leading from the spools 18 are trained. The upper pin 24 is adapted and arranged to be carried into and out of the upper thread supply station 21 and the lower pin 25 is adapted and arranged to be carried into and out of the lower thread receiving station 22 as the arm 26 rocks about its pivotal axis.

At its rear end, the rocker arm 26 is provided with a slot 27 through which projects a pin 28 carried by a vertically disposed operating rod 29 at its upper end. The operating rod 29 is slidably mounted in a U-shaped housing 30 (Figure 5) formed in the frame member 15 and closed by a face plate 31 secured thereto by screws 32. The operating rod 29 projects downwardly beyond the housing 30 and at its lower end it is pivotally connected by a stud 33 to a connecting link 34 at one end thereof. At its other end, the link 34 is loosely mounted on a stud 35 carried by a disk 36 secured to the main drive shaft 16, the arrangement of parts being such that as the main drive shaft 16 makes one complete rotation during a machine cycle of operation the operating rod 29 moves up and down to rock the arm 26 in opposite directions for limited distances about its pivotal axis.

A cam 37 having a high portion 38 and a low portion 39 is mounted on the stud 26a and it is secured to the rocker arm 26 by means of a screw 40 so as to move in unison therewith.

The thread clamping device 23 (as best shown in Figure 5) comprises a bushing 41 and a rod 42, the bushing 41 being threaded through the frame member 15 and forming the stationary part of the clamp and the rod 42 being slidably mounted in the bushing 41 and forming the movable part of the clamp. At its outer end, the bushing 41 is provided with a clamping face 43 and at its outer end, the slide rod 42 is provided with a knob 44 having a clamping face 45 positioned opposite the clamping face 43. The threads 14 leading from the spools 18 are trained between the clamping faces 43, 45. When the clamping device 23 is open, that is, when the clamping faces 43, 45 are apart the threads are free to travel therethrough, but when the clamping device 23 is closed the threads are held against transfer. At its inner end, the slide rod 42 rests against the rounded upper end of a vertically disposed lever 46 secured at its lower end on the inner end of a rock shaft 47 which projects laterally beyond the front side face of the frame member 15. A second vertically disposed lever 49 is secured at its lower end to the outer end of the rock shaft 47. At its upper end, the second lever 49 is provided with a pin 51 positioned before the face of the cam 57. A spring 52 positioned about the slide rod 42 between a collar 53 mounted adjacent the rear end thereof and the bushing 41 tends to force the slide rod 42 rearwardly to maintain the clamping device 23 closed and the pin 51 on the second vertically disposed lever 49 bearing against the face of the cam 37.

The frame member is also provided with a thread drag 60 comprising a plate 62 slidably mounted on and adjusting stud 63 threaded through a clamping face 64 formed on the frame member 15 immediately above the upper thread supply station 21. The three threads 14 leading from the supply spools 18 are trained between the plate 62 and the clamping face 64, and a spring 65 positioned about the stud 63 acts to force the plate 62 towards the face 64 and so

exert a predetermined drag on the threads as they pass therebetween.

The upper thread supply station 21 and the lower thread receiving station 22 are provided with V-shaped members 55, 56 adapted and arranged to guide the threads in fixed paths as they travel through the drag device 60 and through the clamping device 23. To these ends, the members 55, 56 are provided at their ends with holes 61 through which the threads 14 are trained and these holes are so spaced and located as to prevent the threads from moving sideways out of the drag device 60 and the clamping device 23 as they travel therethrough. Since the number of threads may vary depending on the sort of stitch desired, the members 55, 56 are adapted and arranged to be replaceable so that the number of holes in the ends thereof will accord with the number of threads employed. For example, if three threads are employed, the members at their ends are provided with three holes (see Figure 2) whereas if four threads are employed, the members at their ends are provided with four holes (see Figure 6). In addition, since the members 55, 56 are replaceable, they are also adapted and arranged to be used interchangeably to simplify the problems encountered in the manufacture and assembly thereof. To these ends, the members 55, 56 may be stamped from spring steel or the like and they are provided with prongs 57 which may be punched or stamped therefrom and which are adapted to cooperate with notches 58 formed in the frame member 15 to hold them in position.

In operation, the threads leading from the spools 18 are trained through the various parts of the attachment in the manner shown in the drawings and thence in the usual manner through the tensioning devices 19, the thread take-up device 17 and the stitch-forming mechanisms (not shown).

In describing the operation, let it be assumed that the rod 29 which operates the rocker arm 26 is in its lowermost position at the beginning of a cycle of operations (see Figure 1). Under these conditions, the upper pin 24 on the rocker arm 26 is located in the upper supply station 21, the clamping device 23 is closed, the lower pin 25 on the rocker arm 26 is in its outermost position, and a supply of thread adequate to complete a stitch is stored in slack condition in the lower receiving station 22 from whence it is drawn through the tensioning devices 19 by the thread take-up 17 and fed to the stitch-forming mechanism to complete a stitch during the ensuing cycle of operations. During this cycle of operations, the main drive shaft 16 makes one complete revolution and the operating rod 29 is thus forced upwardly and downwardly through the medium of the connecting link 34 in the manner heretofore explained. As the control rod 29 moves upwardly during the first part of the machine cycle of operations, the arm 26 is rocked about its pivotal axis. As the arm 26 rocks about its pivotal axis, the high part 38 of the cam 37 mounted thereon is carried in front of the pin 51 on the vertically disposed arm 49 and the rock shaft 47 is thus rotated. As the shaft 47 rotates, the other vertical arm 46 secured thereto moves forwardly and so forces the slide rod 42 forwardly against the action of the spring 52 to open the clamping device 23 and thus permit the transfer of thread from the upper supply station 21 to the lower receiving station 22. Also, as the arm 26 rocks about its pivotal axis,

the upper pin 24 mounted thereon is carried out of the upper supply station 21 and the lower pin 25 which is also mounted thereon is carried into the lower receiving station 22 to effect the transfer of thread from the upper supply station 21 to the lower receiving station 22 (see Figure 3).

As the operating rod 29 moves downwardly during the latter part of the cycle of operations, the arm 26 is rocked in the opposite direction about its pivotal axis back to its initial position. As the arm 26 thus rocks about its pivotal axis, the low part 39 of the cam 37 mounted thereon is carried in front of the pin 51 at which time the spring 52 acts to force the slide rod 42 rearwardly and so close the clamping device 23 to prevent transfer of thread between the two stations 21, 22. Also, as the arm 26 thus rocks about its pivotal axis, the lower pin 25 is carried out of the lower receiving station 22 and the upper pin 24 is carried into the upper supply station 21. Inasmuch as the clamping device 23 is closed during the travel of the upper pin 24 into the upper supply station 21 thread is drawn from the spools 18 through the drag device 60 and stored in the upper supply station 21 from whence it may be transferred to the lower receiving station during the next cycle of operation. The drag exerted on the threads by the device 60 as they pass therethrough is so regulated by adjusting the position of the stud 63 as to prevent a whipping action from taking place; otherwise excessive amounts of thread might be drawn from the spools 18 and stored in the upper supply station 21 in a tangled condition.

It is to be noted that as the lower pin 25 on the rocker arm 26 moves outwardly after transferring a supply of thread from the upper station 21 to the lower station 22, threads are being withdrawn from the lower station 22 through the tensioning devices 19 by the take-up device 17 to complete the stitch. In addition, it is to be understood that in the formation of a stitch requiring two or more threads more thread may be required from one of the sources of supply than from another. Under all conditions, however, it is desirable that at the beginning of a machine cycle of operations, the lengths of the threads stored in the lower station be at least sufficient to insure the formation of a complete stitch. To this end, the depth of the lower station 22 and the length of travel of the lower pin 25 on the rocker arm 26 are so regulated that when the pin 25 is in its rearmost position in the lower station 22 the length of the most required thread is in excess of that needed to form a stitch by an amount at least equal to the length withdrawn from the lower station 22 after the pin 25 starts its outward movement; and so that this condition may be obtained the depth of the upper station 21 and the length of travel of the upper pin 24 on the rocker arm 26 are regulated accordingly.

While the present embodiment of the invention, the clamp 23 is closed during the latter part of a machine cycle of operation to permit the thread to be stored in the upper supply station 21 and then opened during the early part of the next machine cycle of operation to permit the transfer of the thread from the upper supply station 21 to the lower receiving station 22, other arrangements may be employed depending on the type of machine in which the invention is incorporated. For example, in certain type machines just the reverse might be desired, that

is to say, the clamp may be closed during the early part of a machine cycle of operation to permit the thread to be stored in the upper supply station and then opened during the latter part of this machine cycle of operation to permit the transfer of the thread from the upper supply station 21 to the lower receiving station 22.

In the accompanying drawings, the invention has been shown merely by way of example and 10 in preferred form, and obviously many variations and modifications may be made therein which will still be comprised within its spirit. It is to be understood, therefore, that the invention is not limited to any specific form or embodiment, except insofar as such limitations are specified in 15 the appended claims.

Having thus defined my invention, what I claim is:

1. An attachment for stitching machines presenting a thread storage supply station, a thread storage receiving station, and a rocking member operable first in one direction to draw a given length of thread from a source of supply and store the same in said supply station and then 20 in another direction to transfer the thread from the supply station to the receiving station and store the same therein.

2. The attachment set forth in claim 1 including a clamping device arranged between the two stations and operable to prevent the transfer of thread between the two stations while the thread is being drawn from the source of supply and stored in the supply station.

3. An attachment for stitching machines comprising a frame member having a thread storage supply station, a thread storage receiving station, and a rocking member operable from the main drive shaft of the machine and operable when rotated in one direction to draw a given length of thread from a source of supply and store the same in said supply station and then when rotated in another direction to transfer the thread from the supply station into the receiving station and store the same therein.

4. A thread-feeding device for stitching machines presenting a thread storage supply station adapted to accommodate a length of thread from a supply spool, a thread storage receiving station adapted to accommodate the thread 45 from the supply station, a rocking member for transferring the thread from the supply station to the receiving station, and means for preventing the transfer of thread between the two stations while a new length is being deposited in the supply station.

5. A thread-feeding device for stitching machines presenting a thread storage supply station adapted to accommodate a length of thread drawn from a supply spool, a thread storage receiving station adapted to accommodate thread drawn from the supply station, a rocking member operable to transfer alternately first a length of thread from said spool to the supply station and then to transfer said thread from the supply station to the receiving station, and clamping means operable to hold the thread against transfer from the supply station to the receiving station during the first transfer operation and to release it during the second transfer operation.

6. In a stitching machine equipped with a thread take-up device and a thread supply spool, the combination of a thread-feeding attachment presenting a clamping device, a supply station arranged between the clamping device and the spool and adapted for the storage of

thread therein, a receiving station arranged between the clamping device and the thread take-up device and adapted for the storage of thread therein and a rocking member operable to transfer alternately first a length of thread from the spool to the supply station and then to transfer the thread from the supply station to the receiving station.

7. In or for a stitching machine, a thread-feeding device comprising a thread storage supply station and a thread storage receiving station and a rocking member operable during one phase of a machine cycle of operation for withdrawing thread from a supply spool and storing it in said supply station and operable during another phase of a machine cycle of operation for transferring thread thus stored into the receiving station for subsequent use in the formation of a stitch.

8. In a stitching machine, the combination of a thread storage supply station and a thread storage receiving station, a rocking member operable during one machine cycle of operation for withdrawing thread from a supply spool and storing it in said supply station and operable during the next machine cycle of operation for transferring thread thus stored into the receiving station for subsequent use in the formation of a stitch, and guide members through which said thread passes as it travels into and out of said stations.

9. In a sewing machine, the combination of a thread clamp, a thread storage supply station and a thread storage receiving station located on opposite sides of said clamp, and a rocking member for alternately maintaining said clamp closed and for withdrawing thread from a supply spool and storing the same in said supply station and for thereafter maintaining said clamp open and transferring a portion of the thread thus stored into the receiving station for subsequent use in the formation of a stitch.

10. In a stitching machine, the combination of a clamping device, a thread storage supply station and a thread storage receiving station located on opposite sides of said device, a rocking member for alternately opening and closing

said device during a machine cycle of operation, and means for withdrawing thread from a supply spool and storing the same in said supply station when said device is closed and for transferring a portion of the thread thus stored into the receiving station when said device is open.

11. In a stitching machine, the combination of a clamping device, a thread storage supply station located on opposite sides of said device, means for alternately opening and closing said device during a machine cycle of operation, and a rocker arm for withdrawing thread from a supply spool and storing the same in said supply station when said device is closed and for transferring thread thus stored into the receiving station when said device is open.

12. In a stitching machine, the combination of a clamping device, a thread storage supply station and a thread storage receiving station located on opposite sides of said device, means for alternately opening and closing said device during a machine cycle of operation, and a rocker arm for withdrawing thread from a supply spool and storing the same in said supply station when said device is closed and for transferring a portion of the thread thus stored into the receiving station when said device is open, said device actuating means and said thread withdrawing and transferring means being actuated by a rotating element of the machine.

13. In a stitching machine, the combination of a clamping device, a thread storage supply station and a thread storage receiving station located on opposite sides of said device, means for closing said device during the latter part of a machine cycle of operation and for opening it during the early part of the next machine cycle of operation, and a rocker arm for withdrawing thread from a supply spool during the latter part of a machine cycle of operation and storing the same in said supply station while said device is closed and for transferring during the early part of the next machine cycle thread thus stored into the receiving station while the device is open.

JOSEPH W. BEDARD.
